DISPENSING CONTAINER

William F. Punte, Syracuse, N. Y., assignor to
 Continental Can Company, Inc., New York,
 N. Y., a corporation of New York

Application May 6, 1935, Serial No. 20,082

1 Claim. (Cl. 221—21)

The present invention relates to new and useful improvements in dispensing containers and more particularly to a dispensing container of the type wherein a pouring spout is formed on the control slide for the dispensing opening.

An object of the invention is to provide a dispensing container of the above type wherein a closure member having a spout is slideable in a path which is curved about an axis above and parallel to the top of the container from a closed position wherein the spout portion is below and within the edge of the container to a dispensing position wherein the spout portion projects beyond the edge of the container.

A further object of the invention is to provide a dispensing container of the above type wherein a portion of the top of the container is curved about an axis which is above and parallel to the top thereof and wherein a closure member having a spout portion is similarly shaped to slide within the curved portion from a closed position wherein the spout is below and within the edge of the container to a dispensing position wherein the spout projects above and beyond the edge of the container.

The above and other objects of the invention will in part be obvious and will be hereinafter more fully disclosed.

In the drawing, Fig. 1 is a top plan view of the improved dispensing container.

Fig 2 is a sectional view taken along the line 2—2 of Fig. 1.

Fig. 3 is an enlarged sectional view taken along the line 3—3 of Fig. 1.

The invention relates generally to a metal container which is provided with novel means for dispensing liquid contents without spilling the same. The container is of the conventional metal can type having a body portion and ends seamed thereto. One of the ends is provided with a depressed portion or recess, the lower surface of which is curved about an axis which is above and substantially parallel to the said end. This depressed portion is scored so that it may be conveniently punched through to provide a dispensing opening. A closure member having a dispensing opening therein is fitted in the depressed portion in the can end and is shaped to conform to the curvature thereof so that it may slide about the axis of curvature of the depressed portion. The closure member is shaped to provide a spout at one end thereof. The closure member, when in a closed position, is located entirely below and within the edge of the container. When the closure member is moved to

an open position with the dispensing openings registering with one another, the spout extends above and beyond the edge of the container so as to direct the contents thereof over the container wall.

Referring more in detail to the accompanying drawing, the body portion 10 of the container has an end 11 double-seamed thereto as at 12. The horizontal portion of the end member 11 is disposed below the double seam 12 and is provided with a depressed portion, the lower surface 13 of which is curved about an axis which is above and parallel to the top of the container. The side walls 14 and 14a of the depressed portion are shaped to provide grooves 15 and 15a adjacent the lower surface 13 of the said depressed portion. The curved surface 13 of the can end 11 is provided near one end thereof with score lines 16 through which a dispensing opening may be punched with any suitable implement. A closure member 17 has the lower edge 18 thereof shaped to conform exactly to the curvature of the curved surface 13 on the can end. The side walls 19 and 19a of the closure member 17 are offset inwardly in order to leave outwardly projecting ribs 20 and 20a which fit within the grooves 15 and 15a respectively in the side walls 14 and 14a of the depressed portion on the can end. The closure member 17 is provided with a dispensing opening 21 and with a spout portion 22 at one end thereof. There is also provided a slot 23 extending longitudinally of the closure member 17 and through which a projection 24 on the curved surface 13 extends.

In Figs. 1 and 2 of the accompanying drawing, the full line showing of the closure member 17 indicates the closed position, whereas the dotted line showing of the said closure member indicates its open position. The projection 24 extending into the slot 23 in the closure member 17 serves as a stop for limiting the sliding movement thereof. One end of the closure member 17 may be bent upon itself as at 25 to provide a handle portion by which the closure member may be moved. When it is desired to dispense the contents of the container, the closure member 17 may be moved to the dotted line position shown in Figs. 1 and 2. In this position the dispensing opening 21 in the closure member registers with the scored portion 16 on the can end and in this position the said scored portion may be punched through. It will be noted that the spout portion 22, in this dispensing position, extends above and beyond the double seam 12 so that the contents will be directed over the edge of the con- 55

tainer in order to avoid any spilling. It is to be further noted that the side walls 18, 18a of the closure member provide a channel for directing the liquid contents on to the spout.

- 5 A further feature which should be noted in connection with this dispensing container, is the fact that when the closure member is in a closed position with the dispensing openings out of line, the spout portion 22 and the handle portion 28 are located below the top edge of the container and entirely within the double seam. This feature is of particular advantage in that it permits containers of this type to be stacked one upon the other.
- 10 It is obvious that minor changes in the details of construction and the arrangement of parts may be made without departing from the scope of the invention as set forth in the appended claim.
- 15 20 I claim:

A dispensing container comprising a body, an end seamed thereto, said end having a depressed portion the lower surface of which is curved about an axis above and parallel to said end, the side walls of said depressed portion being shaped to provide grooves adjacent the curved surface thereof, a closure member shaped to conform to the curvature of the lower surface of said depressed portion and having side walls shaped to provide externally projecting ribs, said ribs being adapted to fit within the grooves in said depressed portion whereby the closure member may be moved therein, said closure member being disposed relative to the side of the body so that the spout will project over the side wall of the container when said closure member is in an open position and so that the spout will be disposed beneath the plane of the upper edge of the container when in a closed position.
